UNITED STATES PATENT OFFICE.

JOHN M. KIPP, OF RIDGEWOOD, NEW JERSEY, ASSIGNOR TO RICHARD DIMES CO., OF SOUTH BOSTON, MASSACHUSETTS, A CORPORATION OF MASSACHUSETTS.

DESIGN FOR A SPOON OR ANALOGOUS ARTICLE.

Application filed December 3, 1928. Serial No. 29,093. Term of patent 14 years.

To all whom it may concern:

Be it known that I, JOHN M. KIPP, a citizen of the United States, residing at Ridgewood, in the county of Bergen and State of New Jersey, have invented a new, original, and ornamental Design for Spoons or Analogous Articles, of which the following is a specification, reference being had to the accompanying drawing, forming part thereof, in which—

Fig. 1 is a plan view of a spoon or analogous article showing my new design.

Fig. 2 is an edge view thereof.

Figs. 3 and 4 are cross sectional views, at lines 3—3 and 4—4, respectively, of Fig. 1.

I claim:

The ornamental design for a spoon or analogous article as shown.

In testimony whereof, I have signed my name to this specification.

JOHN M. KIPP.
